LOUIS H. THULLEN, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

1,109,879.

Specification of Letters Patent.

Patented Sept. 8, 1914.

Application filed February 5, 1904. Serial No. 192,145.

To all whom it may concern:

Be it known that I, LOUIS H. THULLEN, a citizen of the United States, residing at Edgewood Park, in the county of Allegheny and State of Pennsylvania, have invented or discovered new and useful Improvements in Railway Signaling Systems, of which the following is a specification.

My invention relates to systems of railway signaling wherein the signals are operated by an alternating signaling current in the track circuits of the system. Both rails of the track are divided into insulated sections corresponding to block sections. The railway cars may be propelled by a direct current or by an alternating current.

It is among the objects of my invention to permit the use of both rails as a return of the propulsion current and at the same time prevent the alternating current in the track circuits from passing from the track circuit of one block section to another.

Referring to the drawings, Figure 1 is a diagrammatic view of one form which my signaling system may assume. Fig. 2 is a similar view of another form of my invention. Figs. 3 and 4 are details showing means for connecting the ends of the rail sections, differing from those shown on Figs. 1 and 2.

Referring to Fig. 1, A is a source of current, here shown diagrammatically as a source of direct current which supplies current to the trolley wire B. Any other form of generator to supply car propulsion current may be substituted for the direct current generator A, for example an alternating current generator. If any such other generator be used, the signaling current will preferably be different from the current supplied by such other generator in some characteristic. For example, if the generator A be an alternating current generator, its frequency will preferably be of a different frequency from the alternating signaling current. The source A of current is connected to the rails of the track through the induction coil P, on a core p, the coil P being tapped at its middle point by the generator connection and having one end connected to one rail, and the other end to the other rail. The windings are in such a direction that the direct current does not unduly magnetize the core of the coil, but will choke down

the alternating signaling current which controls the signal. The track is divided in block sections F, F', and F²; the two rails being both divided at H into pairs of rail sections f and f', f² and f³, and f⁴ and f⁵ corresponding to the block sections F, F', and F², respectively. Each pair of rail sections is insulated from the adjacent pair of rail section except as they are electrically connected in the manner hereinafter indicated. D represents conventionally an electric car having the trolley pole d and trolley d'. L designates a source of signaling current, which preferably is of a different character from the car propulsion current. The source L is here shown, diagrammatically, as being a source of alternating current which feeds the leads 1 to which are connected in parallel the primaries of the transformers E. The secondary e of each transformer is connected to the track rails of its block section, a transformer being associated with each block section or pair of rail sections.

Connected with the rails of each block section are the wires which are connected to the relay K, which is operable by the alternating signaling current only. The arms k of the relays in the position shown bridge or connect the terminals o o of the local circuits which control the signals C.

The track rails of adjacent block sections are connected by inductive windings M and N. As shown the windings M connect the rail sections f, f², and f⁴, and the windings N, the rail sections f', f³, and f⁵. The windings M and N which connect the rail sections of adjacent block sections are associated in pairs with the same metallic core. The pairs of windings M and N are so wound on the core that the direct return propulsion current on the track traverses them in such a direction that the magnetization of the core by the one winding is neutralized by the other. The return propulsion current traverses the rails and the windings constantly in one direction, while the alternating signaling current in any one block section traverses one rail in one direction at any period and the other rail in the opposite direction. Therefore, while the windings M and N are such as to neutralize the effects of the direct current on the cores, the direction of the alternating signaling current through

the combined turns is such as to cause the windings to become choke coils.

The rails of each block section are connected by inductive windings or cross-bondings G of low ohmic resistance to form paths for the car propulsion current, that may traverse the same owing to any difference of potential of the car propulsion current that might exist between the rails. The cross-bondings being inductive are therefore traversed by a small amount of the alternating signaling current, and are used to form a bond on the section to which it is connected so that an alternating signaling current of some definite amount traverses the inductive windings M and N . The cross bonds may be used or not as the case warrants.

Fig. 2 is the same as Fig. 1, except that the windings M' and N' are cross connected between the adjacent block sections as shown. Here the return propulsion current is transposed, the current on one rail section, as f , of one block section passing through one winding to a rail section, as f' , of an adjacent block section. In this form, if the rail insulation between adjacent blocks should break down, as between block sections F^1 and F^2 , the two rail sections each side of the defect would be short-circuited, depriving the relay circuits of so much signaling current that they will be unable to hold their arms k against the contacts o . The opening of the local circuits causes the signals C to indicate danger, as they are so constructed as to indicate a clear track only when the local circuit is closed. The form of invention shown in Fig. 2 has the advantage of tending to neutralize the difference of direct current potential that might exist between the rails due to the proximity of the third rail or other source of current supply. If the car D should enter any block, the alternating signaling current which normally flows through the relay K of that block will largely pass through the wheels and axles of the car, thus short-circuiting the relay. As the relay holds the local signal circuit closed by the action of the alternating signaling current, the said local circuit will at once become opened and its signal thrown to indicate danger. In case one of the rails should break, it is clear that the signal would also indicate danger. As soon as the car passes from the block section or the break has been repaired the circuit through the relay will be restored, causing the local circuit to be closed and the signal to indicate a clear track.

In Fig. 3, I have shown another method of connecting the rails of the block sections. I employ two induction coils, the windings M^2 and M^3 of coils being in series and joining the adjacent ends of the same rail. The windings N^2 and N^3 of the coils are in series and connect the adjacent ends of the other

rail. The windings M^2 , M^3 , N^2 , and N^3 are connected at the point m which is between the two induction coils. The point m is in fact a conductor and connects the middle points of the windings or coils on two adjacent bonds. For example, the windings or coils M^2 , N^2 , may be considered as one winding or coil divided into two equal parts or two windings or coils of the same number of turns joined together. Therefore, the point m is a common middle point or a conductor joining the middle points of the windings or coils of two adjacent induction coils. The return propulsion current would travel, for example, from the rail sections f and f' through the windings M^2 and N^2 , the point m and the windings M^3 and N^3 to the rail sections f^2 and f^3 . The direction of the windings is such in the coils that this return current leaves the cores thereof practically unmagnetized. The signaling current on the rail sections f and f' , for example, will have a path through the winding M^2 , the point m , and the winding N^2 , but as these windings are in the same direction, only a small portion of the signaling current can take this path—not enough to short circuit the relay circuit. In this form of my invention the cross-connections of the rails form paths to equalize the differences of potential of the propulsion that may tend to exist in portions of the track circuit.

In Fig. 4, I employ two induction coils to connect the rail sections. I have shown the rail section f connected through the winding M^4 to the rail section f^2 and through the winding N^4 to the rail section f^3 . The rail section f^3 is similarly connected to the rail section f and f' through the windings M^5 and N^5 . The direction of the windings of these coils is such that the return propulsion current passing through them will not appreciably magnetize their cores. The coils M^4 and N^4 , for example, being wound in the same direction will choke out practically all of the alternating signaling current which would seek a return by way of the windings M^4 and N^4 . A car on a block section will effect the signals the same with the constructions shown on Figs. 3 and 4 as on Figs. 1 and 2.

I do not desire to be restricted to the details shown but claim protection for such modifications as shall come fairly within the spirit and scope of my invention. I have used the words trolley wire but a third rail or other feeder would be obvious equivalents.

I have herein referred to the devices or apparatus between adjacent block sections for permitting the passage of propulsion current as "induction coils." They may be also termed "inductive devices," "inductive windings," "reactances," "reactance bonds" etc.

Having described my invention, what I claim is:—

1. In an electric railway signaling system having closed track circuits, a plurality of block sections each having both rails insulated from both rails of an adjacent block section, a source of alternating signaling current for supplying each closed track circuit with an alternating signaling current, a signal for each block section controlled by said alternating signaling current, a source of current for propelling the cars, and means comprising windings connecting the rails of one block section with the rails of an adjacent block section for permitting the return propulsion current to flow from both rails of one block section to both rails of an adjacent block section. 75
2. In an electric railway signaling system having closed track circuits, a plurality of block sections each having both rails insulated from both rails of an adjacent block section, a source of alternating signaling current for supplying each closed track circuit with an alternating signaling current, a signal for each block section controlled by said alternating signaling current, a source of current for propelling the cars, means comprising windings connecting the rails of one block section with the opposite rails of an adjacent block section for permitting the return propulsion current to flow from both rails of one block section to both rails of an adjacent block section, and a cross inductive winding for each block section. 80
3. The combination in an electric railway system, a source of car propulsion current; vehicles operated thereby; a circuit for said car propulsion current comprising two conductors with which the car makes moving contact, one of which is formed by the track; means for dividing the track to form block sections; signal circuits, at least one for each block section, of which the rails of the track form both sides; a source of signaling current for each signal circuit connected to both rails; a signal device for each signal circuit and completing such signal circuit; and inductive bonds located at the ends of adjacent block sections, the windings of which electrically connect the rails of adjacent block sections, and some of the turns of said windings neutralizing the magnetic effect of other turns of said windings. 85
4. In an electric railway signaling system, closed track circuits, a plurality of block sections, each having both rails insulated, a source of current for supplying the rails of each block section with signaling current, a signal for each block section controlled by said signaling current, a source of direct current for propelling the cars, and a plurality of inductive devices connecting the ends of adjacent rail sections, each inductive device consisting of a pair of windings on a core, the two rails of one block section being connected by one pair of said windings and the rails of the adjacent block section being connected by another pair thereof, the two pairs being electrically connected, the windings being such that the members of each pair are inductive to the signal current and that the propulsion current flowing in said members causes opposing magneto-forces. 90
5. In a signaling system for electric railways, the combination with a plurality of block sections both track rails of which are insulated, of a track circuit for each block section; a source of alternating current supply for each track circuit; a source of current for propelling the cars, the track rails of the block sections forming a return path therefor; and means between adjacent block sections for permitting propulsion current to pass from the track rails of one block section to the track rails of another block section and said means being formed to be unaffected by the passage of the propulsion current through it by reason of opposing magnetic effects created thereby. 95
6. In a signaling system for electric railways, the combination with a plurality of block sections both rails of which are insulated, of a track circuit for each block section, a source of alternating current supply for each track circuit, a source of direct current for propelling the cars, the track rails of the block sections forming a return path therefor; and means between adjacent block sections for permitting propulsion current to pass from the track rails of one block section to the track rails of another block section, and said means being formed to be unaffected by the passage of a direct propulsion current through it by reason of opposing magnetic effects created thereby. 100
7. In an electric railway signaling system, the combination with a plurality of block sections electrically insulated from each other, a track circuit for each block section, a source of alternating current for each track circuit, a relay for each track circuit, a source of current for propelling the cars, a plurality of inductive devices connecting the ends of adjacent rail sections, said devices forming paths of low ohmic resistance to the propulsion current and of high impedance to the alternating current, and conductors connecting adjacent inductive devices. 110
8. In combination, a source of power current; a feeder conductor extending therefrom; a return conductor leading thereto and formed in part by the track rails of a railway; insulation in both track rails for dividing the railway into block sections; inductive bonds connecting the opposite rails of the several block sections; conductors connecting adjacent bonds whereby 115
- 120
- 125
- 130

both track rails will afford paths of the same conductivity; a source of signaling current for each block section; a relay device for each block section; and a signaling device for each block section controlled by the relay of its block section.

9. A system of automatic block signaling for electric railways, embodying two rails divided into sections by insulated joints, reactance bonds arranged to bridge said joints, said bonds each provided with a coil connected across the traffic rails, and bonds of adjacent sections connected together at their centers.

15. 10. A system of automatic block signaling for electric railways, embodying two rails divided into sections by insulated joints, a reactance bond at the opposite ends of each section, said bonds each consisting of a core and a coil thereon, said coil connected across the traffic rails, and a conductor connecting the centers of the coils on opposed bonds in adjacent track sections together.

11. A system of automatic block signaling for electric railways, embodying two rails divided into sections by insulated joints, bonds arranged to bridge said joints, said bonds each having a core and a coil thereon, said coil connected across the traffic rails, and two adjacent bonds connected together at their centers.

12. In a system of automatic block signaling for electric railways, the combination of two electrically continuous rails divided into sections by a break in each rail at the end of each section, the ends of the two rails of a section connected across by a coil, the middle points of the two coils at the end of a section connected together.

40. 13. In a system of automatic block signaling for electric railways and in combination with the traffic rails each divided into block sections by insulated joints, reactance bonds each bond comprising a core, a coil thereon connected across the trackway, and a conductor connecting the middle point of the coils on adjacent bonds.

14. In a system of automatic block signaling for electric railways, and in combination with the traffic rails each divided into block sections by insulated joints, reactance bonds situated at opposite ends of each section, each bond comprising a core, a coil thereon connected across the trackway, and a conductor connecting the middle point of the coils on adjacent bonds.

15. In a system of automatic block signaling for electric railways and in combination with the traffic rails each divided into block sections by insulated joints, reactance bonds each bond comprising a core, a continuous coil thereon connected at one terminal to one rail and its other terminal to the opposite rail of a section, and a conductor connecting

the middle point of the coils on adjacent bonds.

16. In a system of automatic block signaling for electric railways and in combination with the traffic rails each divided into block sections by insulated joints, reactance bonds, each comprising a core, a coil thereon connected at its terminals to the opposite rails of a section, and a conductor leading from the middle point of said coil.

17. In a system of automatic block signaling for electric railways and in combination with the traffic rails each divided into block sections by insulated joints, reactance bonds, each comprising a core and a coil thereon, the coils being connected across the track rails, and conductors connecting the middle points of adjacent coils.

18. A reactance bond comprising a core, a winding having a number of turns surrounding said core, and a conductor leading from a middle point of said winding.

19. A reactance bond comprising a core, a winding thereon having all its turns in the same direction, and a conductor leading from the middle point of said winding.

20. A reactance bond comprising a core, a winding thereon, and a connection from the middle point of said winding whereby when equal currents are sent in opposite directions into said winding from its ends and out at its middle, or vice versa, equal and opposite magneto-motive forces will be produced.

21. The combination with the elements of an automatic block signaling system such as described, of reactance bonds situated at the ends of the block sections, each bond comprising a magnetic core, winding connected across the rails, and a connection leading from the middle point of said winding.

22. An electric railway signaling system having track circuits, insulated rail joints in each rail to electrically separate the track circuits, and a source of current supply for the propulsion of cars upon the railway, in combination with inductive cross bonds connected in pairs from rails on one side of the track to rails on the opposite side of the same track, an electric connection from one cross bond of a pair so connected to the other cross bond of the same pair, the two inductive cross bonds being located respectively on opposite sides of a pair of insulated rail joints, and forming with the said electrical connection a pair of inductive rail bonds across the said pair of rail joints, substantially as described.

23. An electric railway signaling system having track circuits, insulated rail joints to electrically separate the track circuits, a source of current supply for propulsion current, in combination inductive cross bonds having high impedance to a signaling current and low ohmic resistance to a propul-

sion current connected in pairs from rails on one side of the track to rails on the opposite side of the same track, a pair of joints on opposite sides of the track, one of the said 5 inductive cross bonds being on one side of the said joints and the other of said cross bonds being on the other side of the said joints, and an electric connection from a point at or near the center of one of the said 10 cross bonds, to a point at or near the center of the other of said cross bonds, the said electric connection forming in conjunction with one part of each cross bond a rail bond around one of the joints, and forming in 15 conjunction with the remaining parts of the cross bonds a rail bond around the other joint, substantially as described.

24. An electric railway in which the track rails are used as a return path for car propulsion in combination with a source of electric energy for propelling the cars on said 20 railway, insulated joints in both rails to form electrically insulated track sections, a source of current and devices connected therewith for supplying signaling current to 25 the isolated track sections, and inductive devices adjacent each pair of rail joints connected with the track rails and to each other to conduct car propulsion current around 30 said adjacent insulated joints from one track section to the next adjacent, but not the signaling current.

25. In an electric railway system, a source of power current; vehicles operated thereby; 35 a circuit for said power current comprising two conductors with which the vehicles make moving contact, one of which is formed by the track; means for dividing the track to form sections; signal circuits, at 40 least one for each section; a source of signaling current for each signal circuit connected to both rails; a signal device for each signal circuit and completing such signal circuit; an inductive bond located at each end of 45 each section, each comprising a core and a winding which is connected with the track rails; and means connecting the windings of adjacent bonds intermediate their ends whereby the car propulsion current will be 50 conducted from the rails of one section to the rails of the adjacent section and under normal conditions will exert opposite magnetic effects on the cores of the inductive bonds.

55 26. In an electric railway system, a source of power current; vehicles operated thereby; a circuit for said power current comprising two conductors with which the car makes moving contact, one of which is formed by 60 the track; means for dividing the track to form sections; signal circuits, at least one for each section, of which the rails of the track form both sides; a source of signaling current for each signal circuit connected to 65 both rails; a signal device for each signal

circuit and completing such signal circuit; means located at each end of each section for conducting the car propulsion current from the rails of its section to the rails of an adjacent section each comprising a winding 70 electrically connected with the rails of its section, a core for each winding, and an electrical connection between adjacent windings intermediate their ends so that under normal conditions the car propulsion current 75 will exert opposite magnetic effects on the cores, but the signaling current will exert cumulative effects.

27. In an electric railway system, a plurality of track sections; a closed track circuit for each track section; a source of signaling current for each track circuit; a source of propulsion current for vehicles traveling along the railway; an inductive bond located at each end of each track section comprising a winding which is connected with the opposite rails of its track section; and a conductor connecting substantially the middle points of adjacent windings.

28. In a combined system of power transmission and signaling for electric railways, a source of power current; transmitting conductors therefor, one of which normally comprises two equipotential conductors acting jointly to transmit power current simultaneously in the same direction; means for dividing said equipotential conductors into sections; a source of signaling current connected to each section whereby the two conductors thereof act to transmit signaling current in opposite directions; a signaling device connected with each section; windings connected across the conductors of each section; and a conductor connecting equipotential points in the said windings at adjacent ends of sections and serving to transmit the power current from one section to another.

29. In a combined system of power transmission and signaling for electric railways, a source of power current; transmitting conductors therefor, one of which normally comprises two equipotential conductors acting jointly to transmit power current simultaneously in the same direction; means for dividing said equipotential conductors into sections; a source of signaling current connected to each section whereby the two conductors thereof act to transmit signaling current in opposite directions; a signaling device connected with each section; inductive windings connected across the conductors of each section; and a conductor connecting equipotential points in the said inductive windings at adjacent ends of sections and serving to transmit the power current from one section to another.

30. The combination with two traffic rails of a railway both of which are divided by

insulation to form sections, and which act jointly to conduct car propulsion current simultaneously in the same direction; of devices located between the traffic rails of each section through which the propulsion current flows to a point to produce opposite magnetic effects in the device and from there to a corresponding point in a similar device in an adjacent section; a source of car propulsion current; a source of signaling current for each section; a relay device for each section energized by the signaling current; and a railway signal controlled by the relay device.

15. 31. An electric railway the track rails of which are included in the circuit for the propulsion current; insulated joints in both lines of track rails for dividing the rails into sections; a source of alternating signaling current connected across the rails of each section; and means located at each junction of adjacent sections for conducting the propulsion current from the rails of one section to the rails of the other section, said means comprising windings, one terminal of one of which windings is connected to one rail and another terminal of one of which windings is connected to the opposite rail, the magneto-motive force produced in said means by the propulsion current in one rail flowing therethrough opposing the magneto-motive force produced by the propulsion current in the other rail flowing therethrough, and the magneto-motive force produced in said means by the signaling current flowing from one rail to the other being all in one direction.

32. In a combined system of power transmission and signaling for electric railways; a source of power current; transmitting con-

ductors therefor, one of which comprises the two traffic rails acting jointly to transmit power current simultaneously in the same direction; insulating means dividing both traffic rails into sections; a source of 45 signaling current connected to each section whereby the traffic rails thereof act to transmit signaling current in opposite directions; inductive windings connected across the traffic rails of each section; and a conductor 50 connecting equipotential points in the said windings at adjacent ends of sections and serving to transmit the power current from one section to another.

33. In a combined system of power transmission and signaling for electric railways; a source of power current for propelling the cars; transmitting conductors therefor, one of which comprises the two traffic rails acting jointly to transmit power current simultaneously in the same direction; insulating means dividing both traffic rails into sections; a source of signaling current connected to each section whereby the traffic rails thereof act to transmit signaling current in opposite directions; and a plurality of inductive devices connecting the ends of adjacent sections, each inductive device comprising a pair of windings which are connected together in series across the traffic 70 rails of its section, and an electrical connection between inner ends of adjacent pairs of windings.

Signed at Pittsburgh this 2d day of February, 1904.
